UNITED STATES PATENT OFFICE.

ANDREW C. BOSSELMAN, OF NEW YORK, N. Y.

DESIGN FOR A CUP.

SPECIFICATION forming part of Design No. 34,710, dated July 2, 1901.

Application filed May 31, 1901. Serial No. 62,670. Term of patent 3½ years.

To all whom it may concern:

Be it known that I, ANDREW C. BOSSELMAN, residing at 525 and 527 Broome street, New York, in the county of New York and State 5 of New York, have invented and produced a new and original Design for Cups; and I do declare the following to be a full, clear, and exact description of the same, reference being had to the accompanying drawings, forming a part thereof.

Figure 1 is a perspective of my design, and Figs. 2 and 3 are side elevations of the same.

As shown in the drawings, the leading features of my design consist of a cup having 15 pictorial representations of buildings, the head of a buffalo, waterfalls, and shrubbery. These are arranged partly in groups and partly in single figures which are separated

from each other and framed in by ornamental scrolls and flowers *a a*, as shown in the different views. 20

At the upper and lower edges of the cup are unornamented bands *c* and *d*.

Having described my invention, what I claim as new, and desire to secure by Letters 25 Patent, is—

The design for a cup, as herein shown and described.

In testimony whereof I have signed my name to this specification in the presence 30 of two subscribing witnesses.

ANDREW C. BOSSELMAN.
